UNITED STATES PATENT OFFICE

2,355,450

CAR TRUCK

Charles P. Leese, Chicago, Ill., assignor to Standard Car Truck Company, Chicago, Ill., a corporation of New Jersey

Application February 14, 1942, Serial No. 430,889

3 Claims. (Cl. 105—224)

This invention relates to a railway car truck of the type comprising a bolster on which the car body is supported, a pair of side frames, journal boxes, the usual wheels and axles, load carrying springs, and stabilizing means for snubbing or damping the vibratory movements, of compression and expansion, of the load carrying springs. The invention is also concerned, preferably, with a truck provided with roller means between the bolster and side frames to allow lateral movement of the bolster with respect to the side frames. A truck having these two features is disclosed, for example, in United States Patent No. 1,894,385 to E. W. Webb, granted January 17, 1933.

A primary object of the present invention is to provide a railway car truck which will have stabilizing means for the load carrying springs, and also, preferably, lateral motion devices, but which is of novel and improved construction whereby certain advantages, as will be hereinafter set forth, are obtained.

These advantages result from constructions and combinations of parts substantially as follows: The journal boxes are slidably arranged in pedestals or guides at opposite ends of the side frames. The load carrying springs, one or more for each journal box, are disposed between the tops of the journal boxes and the undersurfaces of upper webs of the side frames. Wedges are interposed between the side walls of the pedestals and wedge faces formed on the journal boxes, and stabilizing springs, lighter than the load carrying springs and preferably always under compression, are disposed between the wedges and the upper webs of the side frames.

By these arrangements the relative movements as between the journal boxes and side frames, compressing and permitting the expansion of the load carrying springs, are snubbed or damped by the action of the spring pressed wedges so as to prevent the compression of the springs to their limits which, if it occurs, is likely to result in the breakage of the springs, and in any event, renders the load carrying springs ineffective. According to the present invention, this stabilized spring action takes place, therefore, separately at each wheel without any of the vibratory movements at one wheel being transmitted through the side frames and bolster to the other wheels. This improves the spring support of the car, for example, when the car is travelling over a railway track in which the rail joints are staggered and lessens wear on the moving parts of the spring support of the car.

The bolster is guided in its lateral movements but has no vertical movements and consequently no vertical motion guides so that wear on the bolster is minimized.

Furthermore, it is possible, because there are

no springs between the bolster and side frames, to locate the bearings of the bolster on the side frames, that is the antifriction, lateral motion devices which are disposed between the ends of the bolster and side frames, at low points on said side frames. This makes possible the location of the lateral motion stops, which limit the lateral movements of the bolster, also at low levels, and preferably at substantially the level of the journals, so that when shocks occur between the stops, which may happen occasionally, these shocks will not cause turning thrusts against the side frames, tending to cramp the sliding movements of the journal boxes, which would be likely to occur if the stops were arranged at higher points on the side frames.

The brake rigging, which is hung from the side frames, is spring supported instead of being carried by unsprung side frames, whereby chatter and wear are minimized.

Because there are no springs between the bolster and side frames the depth of the side frames may be reduced, increasing the clearance between the side frames and rails.

The removal of the wheels and journal boxes is facilitated as will be hereinafter described.

The invention is illustrated in the accompanying drawings, which exemplify a preferred embodiment of the invention, and in which

Fig. 1 is a side elevation of the truck.

Fig. 2, a fragmentary side elevation of the same, on a larger scale, with parts of the side frame, journal box and associated elements shown in section.

Fig. 3 is a plan view of one end of the truck.

Fig. 4 is a plan view of the journal box showing, partly in section, the load carrying springs and, on the right hand side, the stabilizing wedge and its spring.

Fig. 5 is a detail sectional view on line 5—5 of Fig. 1; and

Fig. 6 is a detail sectional view, with the scale somewhat enlarged, on line 6—6 of Fig. 5.

It will be understood that the truck comprises two side frames, a bolster, two lateral motion devices, one at each end of the bolster, four journal boxes, each with its load carrying springs or springs, and its pairs of wedges and their stabilizing springs, together with, of course, the usual four wheels, two on an axle. In describing the truck it will be necessary to describe in detail only one of each of the aforementioned truck elements. The others, where appearing in the drawings, will be given the same reference numerals.

Referring to the drawings, the wheels are indicated at 10 (Fig. 1); one of the axles at 11 (Fig. 3); a side frame at 12; the truck bolster at 13; the journal boxes at 14; the load carrying springs, preferably two arranged one within the

other, at 15, 16; the stabilizing wedges at 17; and the stabilizing springs at 18.

The side frames 12 are formed with central openings 19 through which project the ends 20 of the bolster 13 which are formed on their under sides each with a pair of grooves 21 (Fig. 5) to receive the lateral motion rollers 22 which bear on a roller seat 23 formed with two concavities 24, one for each roller. The roller seat 23 is arranged in a recess 25, formed on the lower web 26 of the side frame. If desired, shims 27 may be interposed between the side frames and the roller seats 23 to adjust the elevation of the bolster. 28 is a tie rod which lies under the bolster 13 and connects the side frames 12. Each end of the tie rod is bent over at right angles to the main portion of the rod, as indicated at 29 (Figs. 5 and 6). This bent over end, in each case, projects through a hole in a bracket 30 on the lower web 26 of the side frame, and is perforated at 31 for a cotter pin 32. To prevent vibration a looped spring 33 is provided, the loop 34 of which bears on the rod 28. The spring is coiled at 35—35 around studs 36—36 on the bracket 30 and the ends of this spring 31—37 bear against the lower web 26 of the side frame. By lifting the loop portions 34 of the springs 33, the tie rod may be disengaged from the side frames when this is necessary.

At each end of the side frame is a pedestal or guide comprising side walls 38, 39 (Fig. 2) provided preferably with wear plates 40, and formed with guide flanges 41, 41. The side walls 38, 39 are formed with bottom flanges 42 to which is secured, by bolts 43, a bottom or tie plate 44. The journal box 14 is formed with box-like guide structures 45, 45, projecting into the channeled spaces provided by the guide flanges 41. There are slight clearances preferably between the guide structures and the wear plates 40. These guide structures 45, 45 are formed at their upper ends with oblique webs or wedge faces 46, 46, preferably provided with wear plates 47, 47. The stabilizing or snubbing wedges 17 are arranged in the spaces between the wear plates 47 on the journal box wedge faces 46 and the channeled guides on the side frame. The wedges are formed with horizontal surfaces 48 providing seats for the stabilizing springs 18. The wedges are formed, preferably, with extensions 49 to increase their vertical bearing surfaces. The load carrying springs 15, 16 are interposed between the top web 50 of the journal box and the under side of the upper web 51 of the side frame. The stabilizing springs 18 are interposed between web 51 of the side frame and the wedges 17 and are preferably under some compression when there is insufficient load to compress the load carrying springs 15, 16.

In Fig. 2 the journal box brass is indicated at 52, the wedge at 53, and the wheel journal at 54. The journal box is formed on opposite edges of the oblique wedge surfaces 46 with guide ribs 55, the wear plate 47 being arranged between the guide ribs as indicated at the left hand side of Fig. 4.

56 is a stop lug on the bolster adapted with stop lug 57 on the side frame (Fig. 5) to limit the lateral motion of the bolster. It will be observed that these stop lugs are located at low points on the bolster and side frames so that they are substantially at the level of the centers of the wheel journals 54, as will be apparent from Figs. 2 and 5. In case lug 56 comes into

contact with lug 57 the shock gives no turning thrust to the side frame which, if it occurred, would tend to cramp the movements of the journal boxes.

5 Preferably openings 58 (Fig. 1) are formed in the side frames, and aligned with these openings are openings 59 in the wedges 17. The wheels and journal boxes may be removed by detaching the tie plates 44 from the pedestals of the side frames and jacking up the car by means of jacks placed under the side frames. The operation of removing the wheels and journal boxes is, therefore, much simplified in comparison with that necessary with other types of trucks. When such removal is to be effected, rods can be thrust through the aligned openings 58, 59 to hold up the wedges and stabilizing springs. The load carrying springs will come out with the journal boxes.

I claim:

1. Car truck comprising: side frames having guide members at opposite ends thereof; means for supporting a car body on said side frames with capacity for lateral movement in respect thereto; journal boxes slidably in said guide members; load carrying springs interposed between and engaging the journal boxes and side frames; stabilizing devices for said load carrying springs comprising a pair of wedges interposed between each journal box and adjacent portions of the side frame and springs bearing on said wedges respectively; and said side frames and wedges being formed with aligned openings adapted to receive rods to hold the wedges and stabilizing springs in position when the journal boxes are removed.

2. A car truck comprising side frames, each provided at each end with a pair of spaced vertical, channeled guide members; journal boxes having forward and rear extensions slidably fitted between said pairs of guide members which extensions are formed with vertically extending flat bearing faces of substantial height and width and which merge at their upper ends with oblique wedge faces and with guide ribs at opposite sides of said wedge faces whereby the vertical forward and rear bearings of each journal box for bearing against the guides of the frame are extended above the lower terminations of said oblique wedge faces; load carrying springs interposed between and engaging the tops of the journal boxes and under surfaces of the side frames; wedges arranged between said guide ribs and bearing on said wedge faces and against the adjacent guide members and stabilizing springs between the wedges and opposed under surfaces of the side frames.

3. A car truck comprising: side frames provided at each end with a pair of spaced vertically extending guide members, journal boxes having forward and rear extensions slidably engaging said guide members which extensions are formed with vertically extending flat bearing faces of substantial height and width which unite at their upper ends with oblique wedge supporting faces; load carrying springs interposed between and engaging the tops of the journal boxes and the under surfaces of the side frames; wedges positioned on said oblique faces of the journal boxes and engaging adjacent faces of said vertical guide members and stabilizing springs interposed between said wedges and opposed under surfaces of the side frames.

CHARLES P. LEESE.
